UNITED STATES PATENT OFFICE

2,384,243

GUARD FOR EMERY WHEELS AND THE
LIKE

Andrew Flohr and Alfred J. Flohr, Buffalo, N. Y.

Application February 16, 1944, Serial No. 522,598

7 Claims. (Cl. 51—269)

This invention relates to certain new and useful improvements in protective guards for grinding wheels and like rotating tools.

One of its objects is to provide a guard for tools of this character which is so designed and constructed as to adjustably cover or enshroud the operating side and peripheral portions of the tool while in use and thereby afford maximum protection to the operator at all times and in the event of breakage of the tool, cause any fragments thereof to be deflected away from him.

Another object is to provide a guard for grinding wheels and the like having side sections disposed in overlying relation to the sides of the tool for adjustment toward and from the operating edge or periphery of the tool, and arcuate sections disposed over the periphery of the tool for adjustment circumferentially toward and from each other to expose more or less of the tool-periphery as gaged by the work being operated upon.

A further object of the invention is to provide a safety guard for emery or grinding wheels including a self-adjustable guard wall so mounted as to be displaceable by the work and transparent and shatterproof to enable the operator to observe the work being operated upon, and further so designed as to enable its application to precision grinders and at the same time prevent its marring or damaging the work brought in contact therewith.

Other features of the invention reside in the construction and arrangement of parts herein-after described and particularly pointed out in the appended claims.

In the accompanying drawing:

Figure 1 is a front end view of the guard constituting our invention. Figure 2 is a side elevation thereof, partly in section. Figure 3 is an enlarged fragmentary cross section taken on line 3—3, Figure 2. Figure 4 is a fragmentary front view of a modified form of the guard. Figure 5 is a similar view of another modification thereof. Figure 6 is a cross section taken on line 6—6, Figure 5.

Similar characters of reference indicate corresponding parts throughout the several views.

By way of example, our invention has been shown in connection with a portable tool consisting of an emery wheel 10 attached to a shaft 11 extending through a tube 12 which serves as a handle for the manipulation of the tool by the operator. Disposed substantially over the upper half of the wheel to enclose the periphery and opposite sides thereof is a fixed guard section or

hood 13 having an attaching sleeve 14 projecting axially from the rear side thereof for detachable sliding engagement with the shaft-engaging tube 10. The front wall 15 of this guard section is 10 removable to permit the assembly of the latter over the wheel and the same may be secured in place by screws 16 or like fastenings. This hood leaves the lower portion of the wheel exposed for operative engagement with the work but does not afford complete protection to the operator, and should the wheel break while in use the wheel-fragments will be obviously thrown out in any and all directions with the possibility of serious injury to the operator. To guard against such a condition and insure maximum protection to the operator, we provide movable or displaceable guard means which are disposed over the exposed lower sides and periphery of the emery wheel and which may be set in given positions or be self-adjustable 20 by contact with the work and relative to the sides and periphery of the wheel so that at all times the wheel, with the exception of that portion thereof engaged by the work, is completely enshrouded and the possibility of injury to the operator from flying fragments is reduced to a minimum.

As shown in Figures 1-3, inclusive, these guard means consist of displaceable side plates or walls 17 which are mounted or suspended on the opposite sides of the fixed guard section 13 and arcuate-shaped plates or walls 18 suspended from the peripheral portion of such section. The side plates 17 assume a position in overlying relation to the sides of the wheel revolving tool and their outer edges are of a contour concentric with the wheel and normally extend slightly beyond its periphery. Each side plate is suspended from the companion side wall of the fixed guard section by two sets of pivoted link means 19, 20 to permit a universal displacement of the plate in a plane parallel to the wheel when the latter is brought in contact with the work to expose the wheel for operation on the work. The upper links 19 are pivoted at their upper ends to a common central pivot 21 while the free ends of the lower links 20 are pivoted at 40 22 to the displaceable guard plate 17 at opposite sides of the wheel-axis. A spring 23 connected across the two sets of links serves to yieldingly resist inward displacement of the guard plate and tends normally to urge the same outwardly to a position slightly beyond the periphery of the emery wheel. A stop 24 projecting from the side wall of the guard section 13 below the pivot of the upper links 19 serves to limit the extensible 45 50 55 movement of the two sets of links and the outward

displacement of the guard wall 17. During its displaceable or full-floating movement, each guard plate 17 is confined within a predetermined circumference and for this purpose its opposite side marginal edges are guided in offset lugs 25 formed on the guard section 13.

The arcuate-shaped guard plates 18 which extend over the exposed lower peripheral faces of the emery wheel may be adjustably set in a given position to expose any portion of the wheel desired depending on the work being operated, or they may be yieldingly suspended to normally seek a contracted position to be spread apart by contact with the work as it is presented into operative relation to the wheel. For this purpose each guard plate 18 contains a longitudinal slot 26 through which a clamping screw 27 extends for adjusting the plate circumferentially about the fixed guard section 13. By tightening the screw, the guard plate is held in a fixed position. Disposed between lugs 28 and 29 projecting radially from the guard section 13 and guard plate 18, respectively, is a spring 30, which, upon loosening the clamping screw 27, is adapted to urge the guard plate downwardly about the lower side of the emery wheel. The opposing lower edges of the companion guard plates 18 are provided with curved lips 31 for facilitating the entry of the work therebetween and the spreading of the plates to expose that portion of the wheel as determined by the work. This construction insures complete shrouding of the wheel not used by the work and affords maximum protection to the operator against flying fragments should the wheel become broken while in use.

In Figure 4, we have shown a modification of the side guard mounting, 32 indicating the guard plate which is suspended for radial movement from the fixed guard section 13 by screw and slot connections 33, 34, whereby the plate can be adjusted in or out and then clamped in the position desired.

In precision grinding, it is desired to observe the grinding operation and at the same time prevent marring of the work by contact with other parts. To this end, we have shown in Figures 5 and 6 a guard plate 35 made of a transparent, shatterproof material, such as a plastic or the like, provided at its periphery with equi-spaced anti-friction rollers 36.

We claim as our invention:

1. A protective guard for rotating tools, comprising a housing extending part way over the periphery and opposite sides of the tool, a movable guard wall mounted on said housing in overlying relation to one of the exposed sides of the tool, means for connecting said guard wall with the housing to permit a sliding-like displacement of the former relative to the latter in a plane parallel to that of the rotation of the tool, and a second guard wall adjustably mounted for circumferential movement on and constituting a continuation of the peripheral portion of said housing.

2. A protective guard for rotating tools, comprising a housing extending part way over the periphery and opposite sides of the tool, and independently displaceable guard walls applied to the exposed side and peripheral portions of said

housing and shiftable inwardly and circumferentially, respectively, by contact with the work when the tool is brought into operative engagement therewith.

5. A protective guard for rotating tools, comprising a housing extending part way over the periphery and opposite sides of the tool, independently displaceable guard walls applied to the exposed side and peripheral portions of said housing and shiftable inwardly and circumferentially, respectively, by contact with the work when the tool is brought into operative engagement therewith, and means operatively connecting said guard walls, respectively, with the companion side and peripheral portions of the housing and for guiding them during displacement.

4. A protective guard for rotating tools, comprising a housing extending part way over the periphery and opposite sides of the tool, independently displaceable guard walls applied to the exposed side and peripheral portions of said housing and shiftable inwardly and circumferentially, respectively, by contact with the work when the tool is brought into operative engagement therewith, and means operatively connecting said guard walls, respectively, with the companion side and peripheral portions of the housing and for guiding them during displacement, said means including yieldable and stop elements for normally urging the guard walls to predetermined positions in relation to the tool.

5. A protective guard for rotating tools, comprising a substantially semi-circular housing adapted to extend part way over the sides and periphery of the tool, arcuate-shaped guards applied to the periphery of the housing and adapted to extend over the exposed periphery of the tool for circumferential movement toward and from each other to expose more or less of the tool as determined by the work being operated upon, and means for adjustably connecting said guards to the housing including screw and slot connections and springs for normally urging the guards in opposite directions toward each other upon releasing said connections.

6. A protective guard for rotating tools, comprising a housing extending part way over the periphery and opposite sides of the tool, and a movable guard wall suspended from the housing in overlying relation to one of the exposed sides of the tool for displacement in a plane parallel to the rotating tool and having means connected thereto for yieldingly resisting its movement in any given radially-inward direction; the outer edge of said guard wall having anti-friction work-engaging elements thereon.

7. A protective guard for rotating tools, comprising a housing extending part way over the periphery and opposite sides of the tool, and a movable guard wall suspended from the housing in overlying relation to one of the exposed sides of the tool for displacement in a plane parallel to the rotating tool and having its outer edge substantially concentric with that of the tool, said guard wall being made of shatterproof glass and having anti-friction rollers in its periphery for engagement with the work.

ANDREW FLOHR.
